HERMAN A. AFFEL, OF BROOKLYN, NEW YORK, ASSIGNOR TO AMERICAN TELEPHONE AND TELEGRAPH COMPANY, A CORPORATION OF NEW YORK.

CARRIER-TRANSMISSION-ROUTING ARRANGEMENT.

Application filed July 24, 1919. Serial No. 313,101.

To all whom it may concern:

Be it known that I, HERMAN A. AFFEL, residing at Brooklyn, in the county of Kings and State of New York, have invented certain Improvements in Carrier-Transmission-Routing Arrangements, of which the following is a specification.

This invention relates to multiplex transmission and in particular to multiplex systems in which carrier currents are employed for the transmission of signals.

It has been proposed to multiplex an ordinary wire transmission line such as a telephone or telegraph line by superimposing thereon a plurality of carrier currents of different frequencies, said carrier currents being used for the selective transmission of telephone or telegraph signals. While a system of this character presents the possibility of impressing upon a common wire circuit a number of additional channels of communication by the provision of certain terminal carrier apparatus, it has inherent disadvantage that if any defect should occur upon the common transmission line, such a break, a cross, or a ground, such defect will result in putting out of commission a large number of circuits instead of a single circuit.

In accordance with the present invention it is proposed to overcome this difficulty by providing one or more alternative low frequency transmission lines which are not normally used for carrier transmission so that in the case of trouble occurring upon any line normally used for carrier transmission the terminal carrier apparatus may be disconnected from the line upon which the trouble has occurred and connected to one of the alternative lines so that carrier transmission may take place thereover.

In order to simplify the operation of shifting the carrier channels from a line which is out of order to an alternative line, it is proposed in accordance with this invention to incorporate in the terminal carrier apparatus all or at least a portion of the filtering apparatus which is used for separating the low frequency signaling currents from the high frequency oscillations used for carrier transmission. It is also proposed to arrange the connection so that the switching operations may be performed by a simple switching means, such as a plug and

jack without disarranging the wiring at the terminal station where the carrier apparatus is located.

Since the wire transmission lines which extend between two points over which carrier transmission is to take place may in some instances be two-wire circuits and in other instances four-wire circuits, it is also proposed, in accordance with the present invention, to provide suitable switching means associated with the terminal carrier apparatus whereby such apparatus may be arranged to operate either on a two-wire or a four-wire basis. By the provision of these switching arrangements the same terminal carrier apparatus may be operated on a two-wire basis where the carrier transmission is normally routed over a two-wire line and may be operated upon a four-wire basis when in case of a trouble on the two-wire line it is necessary to shift the connections of the terminal apparatus to an alternative four-wire line. Where the normal routing is over a four-wire circuit and the alternative routing is over a two-wire circuit it is of course obvious that the reverse translation of the terminal apparatus may take place.

The invention may now be more fully understood by reference to the following description when read in connection with the accompanying drawings, Figure 1 of which discloses a circuit arrangement of one modification of the invention; Fig. 2 of which constitutes a circuit diagram embodying two additional modifications of the invention and Fig. 3 of which is a diagrammatic showing of certain details of the terminal carrier apparatus pertaining to a single transmission channel.

Referring to Fig. 1, ML represents a telephone transmission line of the usual character terminating at stations A and B in the usual composite sets CX and CX' of well-known construction whereby the line is composed for transmitting telegraph signals in addition to telephonic signals. In order that the line may be utilized for carrier transmission, branch connections are extended at the stations A and B to jacks I.J and I.J', respectively, these jacks co-operating with the plugs P and P' of terminal carrier apparatus. Low pass filters LF and LF' are

provided at stations A and B for preventing the transmission of carrier oscillations to the terminal telephone circuits LT and LT'. These filters are broad band filters of the general type disclosed in U. S. patents to George A. Campbell Nos. 1,227,113 and 1,227,114, dated May 22, 1917. The filters are so proportioned as to transmit frequencies ranging from zero to the upper limit of frequencies employed in ordinary telephonic transmission while substantially suppressing frequencies above this limit.

The terminal carrier apparatus at station A includes a carrier branch CB terminating in the plug P adapted to cooperate with the jack LJ, said carrier branch including a high pass filter HF. The filter HF is also of the general type disclosed in the patents to Campbell above mentioned and is so designed as to transmit a band of frequencies extending above the upper limit of frequencies employed in ordinary telephonic transmission while substantially suppressing frequencies below this limit. The carrier branch CB is associated through a balanced transformer arrangement 10 with a common transmitting circuit TL and a common receiving circuit RL. A balancing network MN is provided to balance the line ML and associated apparatus at the station A so that the circuits TL and RL are rendered conjugate with respect to each other; that is, disturbances arising in the one circuit will not affect the other. A plurality of low frequency transmission lines L₁ and L₂, etc. are connected to carrier translating arrangements C₁, C₂, etc., said translating arrangements terminating in transmitting channels TL₁, TL₂, etc. and receiving channels RL₁, RL₂, etc., the several transmitting channels and several receiving channels being connected to the common transmitting and receiving circuits TL and RL, respectively.

The function of the carrier translating apparatus is to translate the low frequency signals incoming from the low frequency lines into high frequency carrier oscillations of the frequency assigned to that particular channel for transmission purposes, and to translate high frequency carrier oscillations of the frequency assigned to the particular channel into low frequency signals for transmission over the low frequency lines as well as to provide means for separating the several carrier frequencies into their proper channels. While the details of the carrier translating apparatus form no part of the present invention, a general idea of this apparatus may be had by referring to Fig. 3 which illustrates in simplified form the circuit arrangements of the translating apparatus C₁. It will be understood of course that the translating apparatus of other channels will be similar.

Referring to Fig. 3 the line L₁ is associ-

ated through a balanced transformer arrangement 11 and a balancing network N₁ with transmitting and receiving channels TL₁ and RL₁. The transmitting channel includes a duplex vacuum tube modulator M₁ arranged to normally suppress the carrier frequency supplied thereto over the circuit 20 and to transmit oscillations of the frequency supplied over the circuit 20 modulated in accordance with the telephone signals when telephone currents come in over the line L₁. The filter TF₁ is provided in the output circuit of the modulator M₁, said filter being of the general type disclosed in the patents to Campbell already referred to and being so designed as to transmit a band of frequencies extending from the normal carrier frequency of the channel to a frequency differing therefrom by the range of frequencies ordinarily employed in telephonic transmission. The modulated carrier oscillations transmitted through this filter are amplified by the duplex amplifier TA₁ of well-known construction and are then transmitted through a second filter TF₁' similar to the filter TF₁ and over the terminal portion of the transmitting channel TL₁ to the common transmitting circuit TL of Fig. 1.

The receiving channel RL₁ of Fig. 3 includes a filter RF₁ similar to filters TF₁ and TF₁' already described. A duplex vacuum tube detector operating on the well-known homodyne principle and supplied over the circuit 21 with homodyne oscillations of the frequency assigned to the channel is associated with the receiving circuit RL₁ and operates to detect or translate the modulated carrier oscillations transmitted through the filter RF₁ into low frequency signaling currents. The vacuum tube amplifier RA₁ of well-known construction is provided for amplifying the detected signaling currents which are then passed through a filter RF₁' to the midpoints of the transformer 11 and thence to the line L₁. The filter RF₁' is a low frequency filter similar in construction to the filter LF already described.

The terminal carrier apparatus at the station B is similar to that already described at station A and comprises a plug P' adapted to cooperate with the jack LJ', a high frequency filter HF', carrier branch CB', transformer 10', artificial line MN', common transmitting circuit TL', common receiving circuit RL' and carrier translating arrangements C₁' and C₂' associated with the low frequency lines L₁' and L₂'.

By inserting the plug P in the jack LJ and the plug P' in the jack LJ', carrier transmission may take place between lines L₁ and L₁', between lines L₂ and L₂', etc. over the line ML in addition to the low frequency transmission taking place between the terminal circuits LT and LT'. Should any trouble, however, occur upon

the line ML, said line would not only be out of commission for ordinary low frequency transmission, but would no longer be available for carrier transmission so that the 5 several carrier channels described would also be out of commission. In order to overcome this difficulty an alternative transmission line M_1L is provided, said line including the usual composite sets C_1X and C_1X' and terminating in low frequency telephone 10 circuits L_1T and L_1T' . In order that this line may be used for carrier transmission when desired, low pass filters L_1F and L_1F' similar to filters LF and LF' are inserted 15 in the terminal circuits, and branch connections are provided leading to jacks L_1J and L_1J' adapted for cooperation with the plugs P and P' of the terminal carrier apparatus. As soon as any trouble occurs on 20 the line ML the plugs P and P' may be withdrawn from the jacks L_1J and L_1J' and inserted in the jacks L_1J and L_1J' of the alternative line M_1L so that the carrier transmission may now take place over the line M_1L 25 instead of the line ML.

It will be noted that in making this change no substantial alteration of the alternative or reserve line M_1L is necessary, since the carrier apparatus is all self-contained and the high frequency filters are 30 included in the carrier circuit. It is only necessary to provide the low frequency filters L_1F and L_1F' in the main line M_1L and even these filters would normally be present 35 if repeater points occurred at stations A and B although the line M_1L were only used for low frequency transmission, it being desirable to provide these filters in order to prevent high frequency disturbances due to external causes from being transmitted to the 40 repeaters.

It is possible, however, to arrange the circuits so that even the low pass filters, such as LF may be included in the terminal carrier apparatus with the consequent result 45 that no modification of the ordinary transmission line used as an alternative or reserve route is necessary. An arrangement embodying this additional feature is illustrated 50 in Fig. 2 in which the terminal carrier apparatus at the station A is for the most part identical with that illustrated in Fig. 1, like parts being identified by the same reference characters. The terminal carrier apparatus 55 is modified, however, to the extent that it terminates in two plugs 22 and 23 instead of a single plug P, the low pass filter LF being included in a branch connection extending from the main carrier branch CB 60 to the plug 22. The main line ML extends over the contacts of jacks 26 and 27 and through the composite set CX to the terminal circuit L_1T . By inserting the plugs 22 and 23 in the jacks 26 and 27 the direct connection 65 between the main line ML and the

terminal circuit L_1T is broken and the low pass filter LF is interpolated therein, while the terminal carrier apparatus is branched therefrom through the carrier branch CB and the high pass filter HF. Assuming 70 that a similar arrangement is provided at the station B, carrier transmission may now take place over the line ML.

Should a fault occur in the line ML an alternative line M_1L is provided with jacks 24 and 25 so that the plugs 22 and 23 may be withdrawn from jacks 26 and 27 and inserted in jacks 24 and 25, thereby inserting the low pass filter LF between the main line M_1L and the terminal circuit L_1T , the 80 carrier apparatus being now associated with the main line M_1L through the carrier branch CB.

While in practice the terminal apparatus at stations A and B might be identical, for purposes of illustration, a modified terminal arrangement is shown at station B, the apparatus illustrated at said station being designed so that the terminal carrier apparatus may be associated with either a two-wire line or a four-wire line. In this case the main line ML is connected at station B through the filter LF' to terminal circuit L_1T' and a branch including a high pass filter HF' terminating in a jack 32 is provided for connecting the terminal carrier apparatus to the main line. A second jack 33 connected to an artificial line MN' for balancing the main line ML and its associated apparatus is also provided. Jacks 32 and 34 are adapted for cooperation with plugs 28 and 29 associated with the terminal carrier apparatus.

As an alternative route for carrier transmission the line M_1L is shown as a two-wire 105 line extending from station A to a point intermediate stations A and B, where it is converted to a four-wire circuit including transmission lines LE and LW through the medium of transformer 34 and balancing artificial line M_1N' . Repeaters RE and RW 110 may be included in the lines LE and LW in a well-known manner. The two-wire lines LE and LW which comprise the four-wire transmission circuit are connected through 115 low pass filters LFE and LFW, respectively, to terminal low frequency telephone circuits or apparatus TLE and TLW, respectively. In order to provide for the connection of carrier apparatus to the lines LE and LW 120 branches terminating in jacks 30 and 31 are provided, said branches including high pass filters HFE and HFW. The jacks 30 and 31 are adapted to cooperate with the plugs 28 and 29 of the terminal carrier apparatus 125 already referred to.

The terminal carrier apparatus includes carrier translating arrangements C_1' , C_2' , etc. associated with transmission lines L_1' , L_2' , etc., similar to the corresponding appa- 130

ratus at station A. The carrier apparatus also includes a common transmitting circuit TL' associated through the individual transmitting circuits TL_1' , TL_2' , etc., with the translating apparatus C_1' , C_2' , etc. A common carrier receiving circuit RL_1' is similarly associated through the individual receiving circuits RL_1' , RL_2' , etc. with the translating arrangements.

10 Normally, the common transmitting circuit TL' is connected over the contacts of jack 35, over conductors 36 and contacts of jack 37 to the plug 28. The common receiving circuit RL' is connected over the 15 contacts of jack 38, transformer 39, conductors 40, contacts of jack 41 and over conductors 42 to the jack 29. With the circuits of the carrier terminal apparatus in the condition just described said apparatus is 20 adapted to operate on the four-wire basis and by inserting the plugs 28 and 29 in jacks 30 and 31, carrier transmission may take place over the two-wire line M_1L and the four-wire line $LE-LW$. It will be understood, of course, that the carrier apparatus 25 at station A will be associated with the line M_1L by inserting the plugs 21 and 23 into the jacks 24 and 25.

Carrier transmission from the carrier apparatus at station A passes over the main line M_1L , through the transformer 34, repeater RE, over the line LE , through the high pass filter HFW , over the contacts of jack 31 and plug 29, over the circuit 42, 30 contacts of jack 41, over circuit 40, through transformer 39, over the contacts of jack 38 into the common receiving circuit RL_1' from which point the several carrier transmissions are separated into the circuits RL_1' , RL_2' , etc. Incoming transmissions from the lines L_1' , L_2' , etc. are translated into modulated carrier oscillations by the apparatus C_1' , C_2' , etc. and combined in the common transmitting circuit TL_1' . From this circuit 45 transmission takes place over the contacts of jack 35, over conductors 36, contacts of jack 37, contacts of plug 28 and jack 30, through the high pass filter HFE , over the line LW through the repeater RW and over 50 the line M_1L into the carrier branch CB and thence to the carrier apparatus at station A.

Should it be desired to associate the carrier apparatus with the line ML the plugs 28 and 29 will be inserted in the jacks 32 and 55 33, respectively. The terminal carrier apparatus must now be arranged to operate on a two-wire basis. For this purpose, in addition to the jacks already described, jacks 43, 44, 45 and 46 are provided. Four patching cords terminating in plugs 47-48, 60 49-50, 51-52 and 53-54 are now inserted in the pairs of jacks 35-43, 38-44, 41-45 and 46-37, respectively.

Carrier transmission from station A now 65 passes over the main line ML , through the

filter HF_1' , over the contacts of jack 32 and plug 28, contacts of jack 37 and plug 54, contacts of plug 53 and jack 46, through the transformer 55, over conductor 56, contacts of jack 43 and plug 48, contacts of plug 47 and jack 35 to the common transmitting circuit TL' and thence through the carrier translating apparatus to the individual low frequency lines. Incoming transmissions from the low frequency lines 70 after being translated into modulated carrier frequencies are combined in the common receiving circuit RL' and pass over the contacts of jack 38 and plug 49, contacts of plug 50 and jack 44, through the balanced 80 transformer 57 where the energy divides, part flowing over conductors 58, contacts of jack 46 and plug 53, contacts of plug 54 and jack 37 and over the contacts of plug 28 and jack 32, through the high frequency 85 filter HF' to the main line ML . The other half of the energy is transmitted over the contacts of jack 45 and plug 52, contacts of plug 51 and jack 41, over the circuit 42, contacts of plug 29 and jack 33 to the artificial line MN' . Owing to the balanced 90 relation thus obtained, substantially no energy is diverted through the transformer 55 into the transmitting circuit TL' .

It will be noted that the balanced transformer arrangement 57 is included in the terminal carrier circuit when the carrier apparatus is to be operated on a two-wire basis, said transformer arrangement performing substantially the same functions as that performed by the transformer 34 of the four-wire circuit when the carrier apparatus is operated on a four-wire basis. The essential functions performed by the four patching cords and their associated jacks consist in 100 connecting or disconnecting the balanced transformer arrangement 57, depending on whether the operation is to be on a two-wire or four-wire basis.

It will be understood, of course, that either 110 the line ML or the line M_1L and the four-wire circuit may constitute the normal route for carrier transmission, the other route being an alternative route to be utilized when for any reason the normal route is out of 115 commission. It will also be understood that where the four-wire circuit extends to both carrier terminals the apparatus at both stations A and B may be similar to that at station B.

The invention above described provides a relatively simple and efficient solution for the difficulties arising from the fact that trouble occurring on a line used for carrier transmission results in a large number of 125 circuits going out of service. Furthermore, the apparatus necessary for overcoming the difficulties herein sought to be eliminated is associated either wholly or in part with the terminal carrier apparatus, thereby involv- 130

ing little or no change in the low frequency circuits.

It will of course be obvious that the general principles herein disclosed may be embodied in many other organizations widely different from those illustrated without departing from the spirit of the invention as defined in the following claims:

What is claimed is:

1. In a signaling system, a plurality of transmission lines adapted to transmit low frequency signaling currents and high frequency oscillations of the order employed for carrier transmission, terminal carrier apparatus including means for translating a plurality of independent low frequency signaling currents into high frequency carrier oscillations of different frequencies, and switching means for associating said terminal carrier apparatus with any one of said transmission lines so that carrier oscillations may be transmitted thereover. 70
2. In a signaling system, a plurality of transmission lines adapted to transmit low frequency signaling currents and high frequency oscillations of the order employed for carrier transmission, terminal carrier apparatus including means for translating a plurality of high frequency carrier oscillations into independent low frequency signaling currents, and switching means for associating said terminal carrier apparatus with any one of said transmission lines so that carrier oscillations may be transmitted 80 thereover. 85
3. In a signaling system, a plurality of transmission lines adapted to transmit low frequency signaling currents and high frequency oscillations of the order employed for carrier transmission, terminal carrier apparatus including means for translating a plurality of independent low frequency signaling currents into high frequency carrier oscillations of different frequencies and 90 means for substantially preventing the transmission of low frequency signaling currents to said carrier apparatus, and switching means for associating said terminal carrier apparatus with any one of said transmission lines so that carrier oscillations may be transmitted over 95 said line to establish such connections between the transmission line, a terminal circuit and said last mentioned means that high frequency oscillations transmitted over said line will be transmitted to said terminal 100 carrier apparatus without substantial diversion to the low frequency terminal circuit associated with said line, and low frequency signaling currents will be transmitted over said line to said low frequency terminal circuit without being substantially diverted to 105 said terminal carrier apparatus. 110
4. In a signaling system, a plurality of transmission lines adapted to transmit low frequency signaling currents and high frequency oscillations of the order employed for carrier transmission, terminal carrier apparatus including means for translating a plurality of high frequency carrier oscillations into independent low frequency signaling currents and means for 115 substantially preventing the transmission of low frequency signaling currents to said terminal carrier apparatus, and switching means for associating said terminal carrier apparatus with any one of said transmission lines, said switching means having associated therewith means for substantially preventing the transmission of carrier frequency signaling currents and operating when associated with a given transmission line to establish such connections between 120 125 130
5. In a signaling system, a plurality of transmission lines adapted for the transmission of low frequency signaling currents and high frequency oscillations of the order employed for carrier transmission, low frequency terminal circuits associated with each of said transmission lines to transmit low frequency signals directly thereto, terminal carrier apparatus including means for translating a plurality of independent low frequency signaling currents into high frequency carrier oscillations of different frequencies and means for substantially preventing the transmission of low frequency signaling currents to said terminal carrier apparatus, and switching means for associating said terminal carrier apparatus with any one of said transmission lines, said switching means having associated therewith means for substantially preventing the transmission of carrier frequency signaling currents and operating when associated with a given transmission line to establish such connections between 120 125 130

apparatus, and switching means for associating said terminal carrier apparatus with any one of said transmission lines so that carrier oscillations may be transmitted over said lines to said terminal carrier apparatus while low frequency signaling currents will not be transmitted to said apparatus from said transmission lines.

5. In a signaling system, a plurality of transmission lines adapted for the transmission of low frequency signaling currents and high frequency oscillations of the order employed for carrier transmission, low frequency terminal circuits associated with each of said transmission lines to transmit low frequency signals directly thereto, terminal carrier apparatus including means for translating a plurality of independent low frequency signaling currents into high frequency carrier oscillations of different frequencies and means for substantially preventing the transmission of low frequency signaling currents to said terminal carrier apparatus, and switching means for associating said terminal carrier apparatus with any one of said transmission lines, said switching means having associated therewith means for substantially preventing the transmission of carrier frequency signaling currents and operating when associated with a given transmission line to establish such connections between the transmission line, a terminal circuit and said last mentioned means that high frequency oscillations transmitted over said line will be transmitted to said terminal carrier apparatus without substantial diversion to the low frequency terminal circuit associated with said line, and low frequency signaling currents will be transmitted over said line to said low frequency terminal circuit without being substantially diverted to said terminal carrier apparatus. 100

6. In a signaling system, a plurality of transmission lines adapted for the transmission of low frequency signaling currents and high frequency oscillations of the order employed for carrier transmission, low frequency terminal circuits associated with each of said transmission lines to transmit low frequency signals directly thereto, terminal carrier apparatus including means for translating a plurality of high frequency carrier oscillations into independent low frequency signaling currents and means for substantially preventing the transmission of low frequency signaling currents to said terminal carrier apparatus, and switching means for associating said terminal carrier apparatus with any one of said transmission lines, said switching means having associated therewith means for substantially preventing the transmission of carrier frequency signaling currents and operating when associated with a given transmission line to establish such connections between 110 115 120 125 130

the transmission line, a terminal circuit and said last mentioned means that high frequency oscillations transmitted over said line will be transmitted to said terminal carrier apparatus without substantial diversion to the low frequency terminal circuit associated with said line, and low frequency signaling currents will be transmitted over said line to said low frequency terminal circuit without being substantially diverted to said terminal carrier apparatus.

7. In a signaling system, a two-wire transmission line and a four-wire transmission line, both lines being adapted to transmit low frequency signaling currents and high frequency oscillations of the order employed for carrier transmission, terminal carrier apparatus adapted to operate either on a two-wire or a four-wire basis for the two way transmission of carrier frequencies, switching means to associate said carrier apparatus with either of said transmission lines, and switching means associated with said carrier apparatus whereby the circuits thereof may be adapted for two-wire operations when associated with the two-wire transmission lines, and may be adapted for

four-wire operations when associated with the four-wire line.

8. In a signaling system, a two-wire transmission line and a four-wire transmission line, both lines being adapted to transmit low frequency signaling currents and high frequency oscillations of the order employed for carrier transmission, terminal carrier apparatus for the two way transmission of carrier frequencies, said carrier apparatus including a plurality of carrier channels associated with a common carrier circuit, switching means associated with said common carrier circuit whereby said carrier apparatus may be associated with either of said transmission lines, and switching means whereby when said carrier apparatus is associated with said two-wire transmission lines said common carrier circuit will be connected for two-wire transmission and when associated with said four-wire transmission lines said common circuit may be translated into a four-wire terminal circuit.

In testimony whereof, I have signed my name to this specification this 23rd day of July 1919.

HERMAN A. AFFEL.
